UNITED STATES PATENT OFFICE.

ARTHUR C. MAGRATH, OF BROOKLYN, NEW YORK, ASSIGNOR TO WESTERN ELECTRIC COMPANY, INCORPORATED, OF NEW YORK, N. Y., A CORPORATION OF NEW YORK.

OPERATING MECHANISM FOR CROSSBAR LINE SWITCHES.

Application filed October 15, 1920. Serial No. 417,068.

To all whom it may concern:

Be it known that I, ARTHUR C. MAGRATH, a citizen of the United States, residing at Brooklyn, in the county of Kings, State of New York, have invented certain new and useful Improvements in Operating Mechanism for Crossbar Line Switches, of which the following is a full, clear, concise, and exact description.

10 This invention relates to line switches of the cross bar type such as are used in automatic telephone exchanges for interconnecting subscribers' line and trunk lines extending to first selector switches. More particularly it relates to an operating mechanism for selectively moving the trunk bars of cross bar line switches into positions wherein they can be engaged for the establishment of connections, and for releasing 15 the trunk bars after connections have been established therewith.

In evolving the present invention the object in view was the provision of a mechanism for the above stated purpose requiring 20 a minimum of parts, particularly moving parts, which would be economical to manufacture and which would not be likely to get out of order.

The predominant feature of the present 25 invention is a unitary device which performs the two functions above noted, namely, pre-selecting the trunk bars, that is, setting them into their operative positions wherein they can be engaged by the line bars and releasing the trunk bars after they have been so engaged.

In the co-pending application of J. N. Reynolds Serial No. 416,835, filed October 14, 1920, the mechanism of the present invention is described in connection with a 30 complete cross bar line switch.

With reference to the accompanying drawings; Fig. 1 is a fragmentary cross sectional view of a cross bar line switch taken along the line 1-1 of Fig. 3; Fig. 2 is an end elevation of the trunk bar operating mechanism taken at the left hand end of Fig. 1 showing the trunk selecting commutator and the motor magnet for rotating the mechanism; Fig. 3 is a cross sectional view along the line 3-3 of Fig. 1.

In the preferred embodiment of this invention the trunk bar operating mechanism is situated midway between two groups of 45 trunk bars, that is an upper and a lower

group. Each upper trunk bar is situated directly over a lower trunk bar with which it is electrically connected and with which it is simultaneously operated.

In Fig. 3 there is shown a lower end of an upper trunk bar and the upper end of a lower trunk bar. These are designated by the numeral 1. Between the two trunk bars there is shown the operating mechanism.

Ordinarily cross bar line switches are adapted to accommodate ten or twelve trunk lines. If a switch in accordance with the present invention is intended to accommodate say twelve trunk lines then there would be provided twelve trunk bars in the upper group 50 and twelve in the lower group, or if the switch is intended to accommodate ten trunk lines each group would comprise ten trunk bars.

Each trunk bar is pivotally mounted in the bearings 3, one at each end of the trunk bar. The trunk bars are adapted to rotate through a small angle about their pivots into their preselected positions. In Fig. 1 55 four trunk bars are shown in cross section 70 all of which are in their normal positions except the second one from the right hand side of the figure which is shown in its preselected position. It will be noted that the preselected trunk bar has been displaced 75 through a small angular distance from its normal position.

The third trunk bar from the right in Fig. 1 is seen to be engaged by a line bar 2. This engaged or "busy" trunk bar has been returned to its normal position parallel to the idle trunk bars. The contact springs of the busy trunk bar which are engaged by the line bar are, however, held out of their normal positions. These contact springs being quite flexible permit the trunk bar to return to normal while remaining in engagement with a live bar.

It is essential that only one trunk bar should be in its preselected position at any 100 one time, and it is further essential that as soon as a preselected trunk bar is engaged by a line bar it shall be returned to its normal position and that a succeeding idle trunk bar shall be immediately rotated into its preselected position to be ready for the next 105 call.

Each trunk bar is provided with a laterally extending arm 4 by means of which it is rotated. A flat spring 5 bears against each 110

arm 4 and holds the trunk bar in its normal position when the latter is not displaced from normal by the operating mechanism and returns the trunk bar to normal when it is released from its preselected position.

A shaft 6 extending transversely of the trunk bars is journaled in bearings 7 and 8 and is rotatable, and movable longitudinally therein. A spring No. 9 tends to hold shaft 10 6 in its normal longitudinal position as shown in Fig. 1 and is effective to return the shaft to normal after it has been displaced longitudinally. Shaft 6 is rotatable by means of ratchet wheel 10, mounted thereon 15 and engaged by pawl 11 which is carried by armature 12 of motor magnet 13.

Mounted on shaft 6 and situated at equal intervals are a plurality of disks 14, one for 20 each pair of trunk bars, that is, upper and lower contiguous trunk bars. The disks are rotatable and longitudinally movable with shaft 6. Each disk is provided with two diametrically opposite lugs 15 and two diametrically opposite slots 16, the latter being 25 at right angles to the lugs.

Lugs 15 are operable upon a longitudinal movement of shaft 6 to engage and rotate their respectively associated arms 4, but it is only when lugs 15 are in juxtaposition to the 30 ends of their respective arms 4 that they can engage the latter. At such times one of the slots 16 is in position to clear finger 17, the object of which will be explained. The several disks are arranged with their lugs 15 in 35 different angular positions around the shaft as is clearly shown in Fig. 3, and as a result only one pair of lugs at a time can be in operable relation to a pair of arms 4. At each rotary step of shaft 6 a different pair 40 of lugs are brought into operable relation with their respectively associated pairs of arms 4.

When a trunk bar is rotated into its preselected position it is retained there by means 45 of a latch member 23 which engages lugs 26 of arms 4. Each latch member 23 is pivotally mounted on a pin 24 and is provided with a spring 25 which tends to hold it in normal position. Finger 17 integral with 50 latch member 23 is adapted to operate the latter to release the trunk bar. Finger 17 is engaged by its associated disk 14 upon longitudinal movement of shaft 6 in all positions of the disk except those in which the finger 55 is cleared by one of the slots 16 as illustrated in Fig. 3.

Immediately after each setting up of a trunk bar, into its preselected position shaft 6 together with disks 14 rotates until the 60 next succeeding idle trunk bar is located. Each longitudinal operation of shaft 6 results in the engagement with a disk 14 of the finger 17 associated with the previously preselected trunk bar. Latch member 23 is 65 rotated by its finger 17 upon such engage-

ment and releases the trunk bar permitting its return to normal.

Each longitudinal operation of shaft 6 results in simultaneously releasing one trunk bar and preselecting another. 70

Commutator 20 comprises a plurality of stationary terminals 21 each of which is associated with one of the trunks leading into the switch. Brush 22 fixedly mounted on a shaft 6 successively engages terminals 21 75 upon rotation of the shaft. The circuit of motor magnet 13 is extended through brush 22. When brush 22 engages a terminal 21 which is associated with a busy trunk, the circuit through motor magnet 13 is closed 80 and the latter operates to step shaft 6 around. Each succeeding step of shaft 6 moves brush 22 to the next succeeding terminal 21. So long as brush 22 continues to make contact with terminals 21 which are 85 associated with busy trunks, motor magnet 13 will continue its operation, but as soon as the brush finds a terminal which is associated with an idle trunk, the circuit through motor magnet 13 will be broken and its operation will cease. When brush 22 has come 90 to rest on a terminal associated with an idle trunk a pair of lugs 15 associated with that trunk will be positioned in operable relation to their associated arms 4. The operating 95 mechanism will continue at a standstill until the previously preselected trunk bar is engaged in response to a call whereupon electro-magnet 18 will become energized and pull up its armature 19 imparting a longitudinal movement to shaft 6 thus releasing the engaged trunk bar and rotating the newly selected trunk bar into its preselected position to await the next succeeding call. 100

What is claimed is:

1. A switch comprising a plurality of rotatable bars, contacts therefor, locks for said bars, and a common member controlling said locks.

2. In a switching mechanism, a plurality 110 of rotatable trunk bars; means for rotating said trunk bars individually from normal non-contacting positions into contacting positions, means for locking said trunk bars in said contacting positions and releasing means for said trunk bars, said moving means and said releasing means being common and operable simultaneously.

3. In a switching mechanism, a plurality of rotatable and parallel trunk bars, mechanism for operating said bars individually from normal into preselected position, said mechanism including a rotatable and axially movable member, means operated by said member for locking said bars in operated position, and means for releasing said bars, a rotary and axial movement of said member being effective to cause the preselection or release of any one of said bars. 125

4. In a switching mechanism, a plurality 130

of operable trunk bars, a selective mechanism common to said bars, said mechanism including a rotatable and axially movable member, means carried by said member for selectively operating said bars, means for locking said bars in contacting position, and means carried by said member for operating the second mentioned means.

5. In a switchng mechanism, a plurality 10 of rotatable trunk bars, an operable device therefor comprising a shaft, means carried by said shaft adapted to be moved selectively into operable relation with said bars for releasing said bars, means to impart a 15 longitudinal movement to said shaft for rotating and releasing said bars, and means for retaining said bars into contacting position.

6. In a line switch, a plurality of trunk 20 bars, selective means for moving said trunk bars individually from normal to preselected positions, said selective means comprising a plurality of disks, one for each trunk bar, each of said disks adapted to engage its trunk 25 bar only when situated in a definite angular position, locking means for retaining said trunk bars in their preselected positions, means operative by said disks for releasing said locking means to permit said trunk 30 bars to return to normal, means for rotating said disks simultaneously, and means for moving said disks in operable relation with said trunk bars simultaneously.

7. In a line switch a plurality of trunk 35 bars, selective means for moving said trunk bars individually from normal to preselected positions, said selective means comprising a shaft, a plurality of disks on said shaft, each of said disks being associated with one 40 of said trunk bars and each adapted to engage its trunk bar only when situated in a definite angular position, locking means for retaining said trunk bars in their preselected positions, means cooperative with said disks 45 for releasing said locking means to permit said trunk bars to return to normal, means for rotating said disks, and means for mov-

ing said disks in a direction longitudinal of said shaft.

8. In a line switch a plurality of parallel 50 trunk bars, an operating arm for each trunk bar, a shaft for operating said trunk bars, means for rotating said shaft, means for moving said shaft longitudinally, a plurality of disks on said shaft, one for each operating arm, a lug on each disk adapted to engage said operating arm to rotate the trunk bar associated therewith upon longitudinal movement of said shaft and disks in one direction, said lugs situated in different 55 angular positions relative to one another around said shaft, a locking device for each operating arm adapted to engage the latter when moved into its preselected position, and releasing means for said locking device, 60 said releasing means being operable by said disks upon a longitudinal movement thereof.

9. In a line switch a plurality of parallel 65 trunk bars, an operating arm for each trunk bar attached thereto and projecting laterally 70 therefrom, a shaft normal to said trunk bars, step-by-step means for rotating said shaft, means for moving said shaft longitudinally, a plurality of disks, one for each 75 operating arm mounted on said shaft, said disks rotatable and movable longitudinally with said shaft, a lug on the periphery of each disk for engaging one of said operating arms, said lugs situated in different angular position around said shaft, being so arranged that for each successive rotary step 80 of said shaft a different operating arm will be in operative relation to its respective lug, a plurality of latches, one for each operating arm, each adapted to engage its operating arm upon movement of the latter into its preselected position, and releasing means for each of said latches, said releasing means operable by its associated disk upon longitudinal movement of said shaft. 90

In witness whereof, I hereunto subscribe my name this 7th day of October, A. D., 1920.

ARTHUR C. MAGRATH.
